UNIVERSAL PREDETERMINED AUTOSTOP REGISTER

Charles S. Hazard, Andover, N. J., assignor to
Neptune Meter Company, a corporation of New
Jersey

Application February 17, 1938, Serial No. 190,993

3 Claims. (Cl. 235—132)

This invention relates to presettable registers and more particularly to an automatic presettable register capable of controlling the repeated operations of a device or system for a series of like predetermined registrations without requiring to be reset; the invention being particularly adapted to control the operation of dispensing systems or the like where "batch" operation is desired.

One of the objects of the invention is to construct a register which may be preset to indicate a predetermined amount to be registered and which operates at the termination of the predetermined registration to automatically condition itself in preparation for the initiation of a succeeding registering operation.

Another object of the invention is to construct a register capable of being preset to indicate a predetermined amount to be registered and which operates to indicate both the number or amount actually registered and the number or amount of the predetermined registration still to be registered, the register being so constructed that at the end of the predetermined registering operation it automatically conditions itself preparatory to the initiation of a new registering operation.

Another and more specific object of the invention is to construct a register provided with dual counting devices wherein one of the devices may be preset at a predetermined registration while the other device is in zero position, the register being so constructed and arranged that the dual counting devices operate in opposite directions, the relative operation of the dual counting devices being automatically reversed upon the termination of the predetermined registration in preparation for the initiation of a new registering operation.

A further object of the invention is to construct a register which is adapted to control the operations of a device or system which will automatically cause the operation of such device or system, as the case may be, to cease upon the termination of a predetermined registration, and to automatically repeat such control for any series of successive operations of like quantity or duration without requiring to be reset or readjusted.

A further and more specific object of the invention is to provide a register adapted to control the operation of a dispensing system where "batch" delivery is desired which is capable of being preset to cause the dispensing operation to cease when a predetermined amount of the material being dispensed has been delivered, and

which will automatically repeat such control by causing the dispensing operation to cease for each successive "batch" whenever such predetermined amount has been delivered.

5 An additional object of the invention is to provide my novel predetermined auto stop register with a signalling means which operates automatically to indicate which of the dual counting devices thereof is registering the additive count.

Another additional object of the invention is to provide my novel predetermined auto stop register with an emergency tripping device whereby the operation of the device or system being controlled may be manually caused to cease at any stage during an operation.

Still another additional object of the invention is to provide my novel predetermined auto stop register with a quantity totalizing counter and/or a batch totalizing counter.

The foregoing objects and others ancillary thereto are accomplished by my invention by constructing a register with four sets of counters, two of which I call dual registering indicators, the others comprising a quantity totalizing indicator and a batch totalizing indicator. The dual registering indicators are so arranged that either one may be preset to indicate a predetermined registration while the other is in zero position. The dual indicators are then driven by the device or system to be controlled through a novel reversible clutch connection. The indicator which is in zero position at the initiation of a registering operation operates to indicate an additive count or registration while the preset indicator operates to indicate the amount of the predetermined registration or setting which is yet to be registered, the preset indicator moving retrogressively during the operation to its zero position whereupon the predetermined registration is terminated. Associated with the dual indicators is a cam operated tripping and reversing mechanism which is actuated at, or just prior to the indication of zero by the preset indicator for automatically causing the operation of the device or system being controlled to cease, the reversible clutch to be actuated so as to reverse the relative operating relation of the dual indicators in preparation for the initiation of a new registering operation, and the batch totalizing counter to be actuated to register a unit operation.

The actuation of the reversible clutch mechanism in reversing the relative operating relation of the dual indicators connects the previous additive registering indicator as a preset indicator and the previous preset indicator, which now in-

dicates zero, as an additive registering indicator, no resetting or presetting of the dual indicators being necessary for a repeated operation of the same amount. If the next operation is for a registration different from the last, a hand operated mechanism is so arranged that it may be actuated to adjust the indicator which is in the preset position to indicate the predetermined amount of the next operation. If, however, the same predetermined registration is desired for the next operation, the only step necessary is the restarting of the device or system being controlled which may only require the mere pushing of a control button or the actuation of a lever.

For a more complete understanding of the invention, reference may be had to the accompanying drawings, in which:

Figure 1 is a view in front elevation of the register when used in connection with the meter and flow control valve of a fluid dispensing system;

Figure 2 is an enlarged view in front elevation of the registering mechanism with the casing removed and parts broken away;

Figure 3 is a view in elevation of the left side of Figure 2;

Figure 4 is a view in plan of the registering mechanism shown in Figure 2 with the gear compensating structure removed;

Figure 5 is a view in front elevation of the dual registering indicators and associated mechanism with parts broken away;

Figure 6 is a vertical sectional view taken along the line 6—6 of Figure 5;

Figure 7 is a vertical sectional view taken along the line 7—7 of Figure 4;

Figure 8 is a view in plan of the tripping mechanism shown in Figure 7;

Figure 9 is an enlarged vertical sectional view taken along the line 9—9 of Figure 5 with a part broken away;

Figure 10 is an enlarged vertical sectional view taken along the line 10—10 of Figure 5 with parts broken away to show the interior structure of a units wheel of the dual indicators; and

Figure 11 is a view in elevation of a modified form of a portion of the control mechanism.

For purposes of illustration, I have shown in Figure 1 an embodiment of my invention enclosed in a casing 12 in combination with a fluid measuring or dispensing system comprising a meter 13 and a flow control valve 14. The meter 13 may be of any desired type which upon the passage of liquid or other fluent material therethrough operates to transmit a shaft movement corresponding to the quantity of the material passed therethrough. The valve 14 is of the self closing type, the closing of which is controlled by the register as hereinafter described. The register itself comprises dual registering indicators 15 and 16 which are exposed through windows in the face of the casing 12. A glass or other transparent plate 17 extends over the face of the casing and prevents dust or moisture from entering through the windows. Associated with the dual indicators is a signalling or disclosing device 18 which operates to indicate or otherwise render it apparent which of the dual indicators is operating as the additive counter during a registering operation. Exposed through other windows are also a quantity totalizing counter 19 and a batch totalizing counter 20.

The mechanism for driving the dual indicators 15 and 16 is best shown in Figures 2, 3 and 4. 75

The meter shaft 21 is coupled by means of a shaft 22 to a gear compensating mechanism indicated generally at 23 which is adapted to calibrate the registering device to coordinate it with the particular meter with which it is associated in order to accurately register the quantities of liquid flowing through the meter. This compensating mechanism is also adapted to enable adjustments to be made to insure accurate registration when measuring the flow of fluids of different viscosities, or to enable correction for changes in the viscosities and/or temperature of the particular fluid being measured. A gear compensating mechanism of this type is fully disclosed in the patent to W. L. Marden, No. 1,970,526, issued August 14, 1934.

A shaft 24 operatively connects the compensating mechanism 23 with a reduction gear train 25 which is provided for reducing the relatively high operating speed of the meter shaft to a rate suitable for operating the register and associated tripping mechanism.

A register drive shaft 26 is driven by the reduction gear train 25 through a gear 28 carried by the shaft 26. A worm 30 mounted on the upper portion of the vertical shaft 26 drives a worm gear 32 secured to a horizontal shaft 33 upon which a five lobe cam 34 is axially mounted by means of a sleeve 36. The horizontal shaft 33 which is supported in part by the frame member 37 supports a spur gear 38 which meshes with the peripheral gear teeth 40 of a crown gear 42 carried by a shaft 43.

Mounted on two spaced struts 44 and 45 of the frame-like housing 46 of the register are two bearings 47 and 48. A reversing shaft 49 is rotatably and slidably mounted within the bearings 47 and 48. Rotatably mounted on the bearing 47 is a clutch gear 50 which is adapted to mesh with the crown gear 42. A like clutch gear 51 is rotatably mounted upon the bearing 48 for meshing engagement with the crown gear 42 at a point diametrically opposite to the point of engagement of the clutch gear 50. The engaging relation of the clutch gears 50 and 51 with the crown gear 42 at diametrically opposite points causes these gears to rotate in opposite directions.

In order to selectively transmit the motion of the clutch gears 50 and 51 to the reversing shaft 49, each of the gears 50 and 51 is provided with a laterally projected clutch pin 52 and 53, respectively. A circular clutching element 54 secured to the reversing shaft 49 between the bearings 47 and 48 is provided with a plurality of laterally extended fins 55 and 56 on opposite sides adjacent the peripheral edge thereof. These laterally extended fins 55 and 56 are adapted to engage the pins 52 and 53 depending on the position of the clutching element 54. As shown in Figures 4 and 5, one of the fins 55 is in engaging relation with the pin 52 so that the clutching element 54 is adapted to be driven by the clutch gear 50. The fins 55 and 56 are staggered with respect to each other so that one of the pins 52 or 53 may be effectively disengaged and the other engaged by a quick shifting movement of the clutching element 54 without the occurrence of any appreciable relative movement between the driving clutch gears 50, 51 and the driven clutching element 54.

The dual registering indicators 15 and 16 may comprise any desired number of counter wheels or drums, three each being shown for purposes of illustration. Referring to Figure 5, the indi-

cator 15 consists of a units wheel 60, tens wheel 61 and a hundreds wheel 62, each rotatably mounted on a shaft 64. The numeral wheels of the indicator 15 are driven by the reversing shaft 49 by means of an elongated pinion 65 carried by the shaft 49, an idler gear 66, and a gear 67 carried by the sleeve 68 which is rotatably mounted on the shaft 64. The sleeve 68 is provided with a disk 69 which slidably engages the peripheral side edge of the units wheel 60, and which pivotally supports a pair of L-shaped pawls 70 and 71. The pawls 70 and 71 are urged into engagement with slots 72 formed on the inner surface of the units wheel 60 by a spring 75 sufficiently strong to maintain the pawls 70 and 71 in driving engagement with the slots 72 for transmitting movement for both directions of rotation of the sleeve 68 to the numeral wheel 60.

The left side portion of each of the numeral wheels 60, 61 and 62, as viewed in Figures 2 and 5, is provided with a control disk 76 which has a cut out portion or notch 77, the purpose of which is described in detail hereafter. Contiguous the control disk 76 on the units wheel 60 are the usual lock disk and mutilated gear 78 and 79, respectively, which operate the usual transfer pinion 80 for moving the tens wheel 61 through one tenth of a rotation for each complete rotation of the units wheel in accordance with the Geneva transfer movement. The gear 81 which is associated with the tens wheel 61 and which meshes with the transfer pinion 80 may have driving engagement with the tens wheel by means of pawls and slots identical to those by which the disk 69 drives the units wheel, it being recognized, however, that the gear 81 may be directly secured to the tens wheel for the purpose of this invention. The hundreds wheel 62 is driven from the tens wheel by the same Geneva transfer movement employed between the units and tens wheels 60 and 61.

For the purpose of presetting the numeral wheels of the indicator 15 for a predetermined registration, a spline 82 is provided in the shaft 64. A pawl 84 is mounted upon the inner side of the units wheel 60 and is urged against the shaft 64 by means of a spring 85. The tens and hundreds wheels 61 and 62 are not provided with pawls for engagement with the spline 82, their movement for both the presetting and the registering indicating operations being received solely through the Geneva transfer movement from the units wheel 60. A gear 86 is carried by the shaft 64 and is adapted to be engaged by the spur gear 87 secured to a manually actuated shaft 89 slidably and rotatably mounted in the frame 46. The shaft 89 is adapted to extend through the casing 12 where a hand crank 90 is secured thereto. The indicator 15 may therefore be preset by manually shifting the shaft 89 so as to engage the gears 86 and 87. The crank 90 may then be actuated to rotate the shaft 64, the spline 82 thereof engaging the pawl 84 to move the units wheel 60 and the associated numeral wheels 61 and 62 through the Geneva transfer movement to the setting desired.

The presetting movement of the numeral wheel 60 by the operative engagement of the pawl 84 and the spline 82 is permitted by the pawl and ratchet connection between the numeral wheel 60 and the disk 69. In this connection it may be added that subtractive or counterclockwise movement of the numeral wheels 60, 61 and 62, as viewed in Figure 10, will cause the pawl 84 to rotate the shaft 64. This resulting movement of

the shaft 64, however, is of no consequence, since the shaft is normally free to idle. This is also true of the shaft 97.

The lower registering indicator 16 is of a construction identical with that of the upper registering indicator 15, it being driven by the pinion 65 which meshes with a gear 92 carried by the sleeve 93. The units wheel 94 of the indicator 16 is driven from the sleeve 93 by a pawl 10 and ratchet connection identical to that illustrated in connection with the numeral wheel 60. The numeral wheels of higher order of the indicator 16 are driven from the units wheel 94 by the usual Geneva transfer movement which includes the transfer pinions 95.

The registering indicator 16 is adapted to be preset in the same manner as the registering indicator 15, the manually actuated shaft 89 being capable of moving the gear 87 into meshing engagement with the gear 96 carried by the shaft 97 upon which the registering indicator 16 is mounted.

The reversing and tripping mechanism which is actuated by the predetermined operation of the dual registering indicators 15, 16 and the movement of the five lobe cam 34, is best illustrated in Figures 2, 3, 4, 7, 8 and 9.

A cam actuated lever 98 is pivotally mounted on a bevelled bearing 99 carried by a stationary shaft 100 and provided with a laterally extended cam roller 102 adapted to engage the lobes of the cam 34 when the lever 98 is moved into an engaging position therewith, the lever 98 being biased to a non-engageable position by a spring 103. The initial movement of the lever 98 is controlled by one of the indicators 15 or 16 through a bell crank member 106 or 107, as the case may be, the latter being pivotally mounted on stationary shafts 104 and 105, respectively. A plurality of rollers 108 are rotatably mounted on a shaft 109, carried by the bracket-like arm 110 of the bell crank member 106, for engagement with the control disks 76 associated with the numeral wheels 60, 61 and 62 of the registering indicator 15. A plurality of rollers 111 are likewise rotatably mounted on the lower arm of the bell crank member 107 for engagement with the control disks associated with the numeral wheels of the registering indicator 16. Each of these bell crank members are urged by means of springs 112 and 113 to cause the rollers 108 and 111 to bear in riding relation against their respective control disks.

The vertically extended arms 114 and 115 of the bell crank members 106 and 107, respectively, are positioned to engage the side of the cam actuated lever 98. When all of the numeral wheels of one of the dual indicators 15 or 16 reach or enter zero position, such as illustrated by the position of the indicator 16, the notches 77 of each of the controlling disks 76 associated with the numeral wheels of the zeroizing indicator also enter alignment, whereupon the associated rollers tend to move therein causing the vertical arm of the respective bell crank to swing the lever 98 into engaging position with the cam 34. Referring particularly to the indicator 16, as the notches of the control disks thereof come into alignment, the rollers 111 are urged into the notches causing the bell crank 107 to rotate in a counterclockwise direction, as viewed in Figure 3, thereby moving the cam actuated lever 98 to a position where the laterally extended roller 102 overlies the cam 34. As the cam 34 revolves, one of the lobes thereof will engage the roller 102 and

pivot the lever 98 in a clockwise direction, as viewed in Figure 7, about the shaft 100. A latch member 116, which is pivotally mounted on the shaft 100 adjacent the cam actuated lever 98 is provided with a laterally extended lug 117 which rides on the lever 98. The clockwise movement of the lever 98, therefore causes the latch member 116 to also move and trip a latch engaging lever 118, whereby the operation of the device or system being controlled is stopped.

The spring 103 previously described in connection with the lever 98 may be dispensed with by providing a positive connection between the lever 98 and the bell crank members 106 and 107. Such a positive operating connection is illustrated in Figure 11. The vertically extended arms 114a and 115b of the bell crank members 106a and 107b, respectively, are pivotally connected at 119 and 121 to the opposite ends of a link 123 having an elongated slot 125 adapted to receive the free end of the lever 98. When the indicator 16, for example, reaches zero position, the tension of the spring 113 causes the rollers 111 to move into the corresponding notches 77 of the associated control disks 76, thereby rotating the bell crank 107b counterclockwise. The counterclockwise movement of the bell crank arm 115b causes the slotted link 123 to also rotate counterclockwise about the pivot connection 121 and move the lever 98 to the left where the roller 102 thereof is adapted to be engaged by the meter driven cam 34 for tripping the latch elements 116 and 118. When the indicator 15 reaches zero position in a succeeding operation, the bell crank arm 114a is caused to move in a clockwise direction to rotate the link 123 clockwise about the connection 121, thus moving the lever 98 again to the left similarly as when the indicator 16 moves to zero position. The initial actuation of the units wheel upon initiation of a succeeding operation causes the rollers 108 or 111, as the case may be, to move out of the notches 77 of the associated control disks 76 and causes the link 123 to be returned and the lever 98 retracted from its cam engaging position.

For the purpose of reversing the driving direction of the shaft 49, and therefore the operating direction of the dual indicators 15 and 16, a clutch actuating member 120 is pivotally mounted on a shaft 122 by an integral sleeve 124. The upper portion of the clutch actuating member 120 is provided with a laterally supported roller 126 which operatively engages the end flanges 127, 128 of a sleeve 129 carried by the reversing shaft 49. A four cornered cam 130, the side edges of which are curved inwardly between the four corners thereof, is carried by a shaft 132. A pair of laterally supported rollers 134 and 135 are so located on the clutch actuating member 120 that they engage the peripheral edge of the cam 130 at points about 135 degrees apart, one of the rollers riding on the low portion of a side edge of the cam and the other on a corner portion thereof. Secured to the shaft 132 to the left of the cam 130, as viewed in Figure 6, is a ratchet wheel 140 by which the cam 130 is driven.

The latch lever 118 which is adapted to engage the latch member 116 is rotatably mounted on the shaft 132 adjacent the ratchet wheel 140. The lever 118 is provided with a laterally extended arm 141, which pivotally carries a pawl 142 arranged to engage the teeth of the ratchet wheel 140. The latch lever 118 may be urged in a clockwise direction, as viewed in Figure 7, against the latch 116 by any appropriately located spring or other biasing means. In the illustrated embodiment

of the invention, the spring 143 of the self-closing valve 14 is utilized for this purpose. When the latch 116 is rotated in a clockwise direction by the cam actuated member 98, the latch lever 118 is released and, due to the compression of the valve spring 143, the lever 118 is caused to rotate clockwise to a position indicated by the broken lines in Figure 7.

The clockwise movement of the lever 118 causes a rotation of the shaft 132 and the four cornered cam 130 carried thereon by the engagement of the pawl 142 with the ratchet wheel 140. For each clockwise movement of the lever 118, the four cornered cam 130 is moved through 45 degrees causing the engaging rollers 134 and 135 to reverse their respective positions on the high and low portions of the cam 130, thereby pivoting the member 120 in either a clockwise or counterclockwise direction, as viewed in Figures 2 and 5, depending upon the relative positions of the rollers 134, 135 on the cam 130 at the beginning of the latch tripping movement. In the position illustrated, the movement of the clutch actuating member 120 would be in a clockwise direction. This movement of the member 120 would operate to move the shaft 49 and the clutch element 54 to the right, thereby disengaging the clutching element 54 from the clutch pin 52 and bringing it into clutching engagement with the projected pin 53 carried by the gear 51. The next rotation of the four cornered cam 130 through another 45 degrees would cause the clutch actuating member to pivot in a counterclockwise direction, thereby reversing the engagement of the clutching element 54 back into engaging relation with the projected pin 52 carried by the gear 50.

The reversing movement of the member 120 is given a snap action by means of a spring urged toggle member 144 which pivotally engages a conical recess in the surface of a laterally projected lug 145 carried on the member 120. The upper end of the member 144 is slidably held by an eye member 146 carried by the end of the stationary shaft 100. A spring 147 coiled about the member 144 between the eye member 146 and the conical head 148 of the member 144 provides the necessary tension. As the member 120 is moved across dead center, the spring urged member 144 operates to snap the moving member 120 to its new position. This snap action is repeated in the opposite direction when the member 120 is returned.

The device or system to be controlled by the predetermined operation of the dual indicators 15 and 16 is operatively connected to the latch arm 118. In the illustrated embodiment, a rod 149 is shown pivotally connecting the control lever 150 of the flow control valve 14 to the lever 118. A bracket member 152 mounted on the flow control valve pivotally supports the lever 150. A roller 154 carried by the lever 150 is adapted to engage the valve stem 156 upon a counterclockwise movement of the lever 150 to actuate and hold the valve 14 in open position. Clockwise movement of the control lever 150 caused by the tripping of the latch lever 118 permits the valve 14 to automatically close, thereby terminating the flow of liquid through the meter 13.

Any appropriate signalling means may be provided to indicate which of the dual indicators 15 and 16 is operatively connected to register the positive count. In some cases it may be desirable to provide a shutter arrangement operable at the initiation of each registering operation to expose the numeral wheels of the indicator con-

nected to register the particular operation. However, in the embodiment illustrated (Figures 1 and 5) the signalling device 18 is shown as comprising a signal plate 160 located between the indicators 15 and 16 and connected by a link 161 to a laterally extended arm 158 carried by the clutch actuating member 120. The signal plate 160 is provided with two sets of arrows, 162 and 163, each set pointing in the opposite direction and spaced from each other. In each position, one set of the arrows 162 or 163 will be exposed at the window 17 pointing toward the registering indicator which is operatively connected to indicate an additive registration. When the driving connection of the clutch element 54 is reversed, the signal plate 160 is at the same time shifted to expose the other set of arrows indicating that the operative connection of the dual registering indicators has been reversed and that the next additive registration will be registered on the indicator to which the exposed arrows point. While a signalling arrow has been provided for each numeral wheel of the dual indicators 15 and 16, it is recognized that one arrow only for each of the dual indicators 15 and 16 would suffice and that other forms of signalling or disclosing means may be substituted therefor and still be within the purview of my invention.

In order to insure the presetting of only the indicator which is properly connected for presetting purposes, the clutch actuating member 120 is so designed and positioned that the manually actuated gear 87 is prevented from meshing with the gear carried by the shaft of the indicator which registers zero. More specifically, a roller 164 is provided on an arm of the member 120 and is adapted to overlie the gear 96 when the indicator 16 is in zero position, thereby preventing the gear 87 from being brought into meshing engagement with the gear 96. The gear 87, however, may be brought into meshing engagement with the gear 86 for the purpose of presetting the numeral wheels of the indicator 15 to indicate the predetermined amount or quantity to be registered during the subsequent registering operation. When the member 120 is shifted and the indicator 15 is in zero position, the end of the shaft 49, which carries the collar 129, will be in a position beneath the gear 86 where it prevents the gear 87 from being brought into engagement with the gear 86, the roller 164 being moved to permit engagement of the gear 87 with the gear 96. In this position, the indicator 16 may be adjusted to indicate a different predetermined registration or it may be left undisturbed if it is desired to repeat the amount of the preceding operation.

The operation of my novel automatic presettable register when used with a fluid dispensing system is as follows:

Assuming that the indicator 16 has been preset to indicate 321 gallons or other units of the material to be measured, the dispensing operation may be initiated by the actuation of the control lever 150 in a counterclockwise direction to the position shown in Figure 1, whereby the valve stem 156 is depressed to open the flow control valve 14 and the lever 118 moved into latch engagement with the latch member 116. The flow of fluid through the meter drives the shafts 22 and 24, which are operatively connected by the gear compensating mechanism 23. The shaft 24 is driven by the shaft 24 through the medium of the train of reduction gears 25. The worm gear 30 carried by the shaft 26 drives the crown gear

42 through the medium of gears 32 and 38. The clutch gears 50 and 51 are rotated in opposite directions by the crown gear 42. The clutching element 54 is driven by the engaging pin 52 of the clutch gear 50 to rotate the shaft 49 and the driving pinion 65. The idler gear 66 enables the driving pinion 65 to drive the indicators 15 and 16 in the opposite direction, the indicator 15, for this operation, being driven to indicate the amount of predetermined registration actually registered; the indicator 16 being driven to indicate the amount of the predetermined registration yet to be registered.

Just prior to the termination of the predetermined registration, the notches 77 of the control disks 76 associated with the dual indicator nearing zero position, begin to come into alignment thereby permitting the corresponding rollers 108 or 111, as the case may be, to be moved therein with a resultant rotation of the bell crank member upon which the rollers are mounted. In the present operation the indicator 16 will be the one approaching zero position, since it was the indicator assumed to be preset at the reading of 321 units. As the notches 77 of the control disks 76 associated with the numeral wheels of the indicator 16 approach alignment, the bell crank 107 will rotate clockwise, as viewed in Figure 3, causing the arm 115 to shift the cam actuated lever 98 to the left, whereby the roller 102 is brought into a position overlying the cam 34. While in this position, the roller 102 will be engaged by a lobe on the meter actuated cam 34 causing the member 98 to pivot upwardly about the shaft 100. The upward movement of the member 98 in turn causes the latch 116 to be pivoted in a clockwise direction, as viewed in Figures 2 and 7, by engagement with the overlying lug 117 to disengage the latch lever 118.

Upon the disengagement of the latch lever 118 from the latch 116, the compression of the valve spring 143 causes each of the levers 159 and 118 to swing clockwise as viewed in Figures 1 and 7, respectively, whereby the valve 14 is closed and the four cornered cam 130 rotated 45 degrees through means of the pawl and ratchet connection 140, 142. The partial rotation of the cam 130 through 45 degrees actuates the clutch actuating member 120 to simultaneously shift the signal plate 160 and the clutch element 54 to their reversed positions. The notches 77 in the controlling disks 76 are so positioned with respect to the numeral wheels that the flow control valve is adapted to be fully closed, with the reversing operation snapped to completion, by the time the numeral wheels of the dual indicators indicate the termination of the predetermined registration, the indicator 16 displaying a reading of 321 while the previously preset indicator 16 registers zero. As shown in Figures 1 and 2, the tripping mechanism is in the position reached just prior to the disengagement of the latching elements 116 and 118. After the valve has been closed and the clutch element 54 shifted to its reversing position, the register may again be set in motion to repeat the same predetermined registering operation by the mere actuation of the lever 150 to open the flow control valve 14.

For the purpose of stopping the device or system being controlled during a registering operation, I have provided an emergency tripping element 185 which may be actuated by the mere pushing of an exposed button 186. This emergency tripping element 185 comprises an elong-

gated flat member with one edge thereof bevelled at 167, as shown in Figure 4, to engage a lug 168 on the latch 116. A slot 170 is provided in the strut 45 of the frame structure to slidably support an edge of the tripping member 165 so that when the member is moved inwardly the bevelled edge 167 will be caused to force the latch 116 to pivot in a clockwise direction and release the lever 118, the tripping member 165 being retracted by a spring 171. As previously described, the releasing of the lever 118 from the latch member 116 permits the valve 14 to close and immediately stop the flow of liquid through the meter 13.

The quantity totaller 19 comprises a series of numeral wheels as illustrated in Figure 2. The quantity totalizer is driven from the shaft 26 by the worm 172 and the train of gears 173, 174 and 175. The unit or numeral wheel 176 of lowest order of the quantity totalizer is driven directly from the gear 175. The remaining number wheels, each of which are of a succeeding higher order, are driven from the numeral wheel 176 by means of the usual Geneva transfer movement including transfer pinions 177.

The batch totalizer 20, which may or may not be of the resettable type, is driven by a crown gear 180 secured to the shaft 132 to the right of the four cornered cam 130 as viewed in Figure 6. An inter-engaging idler gear 182 drives the units wheel of the batch totalizer 20 from the crown gear 180, the numeral wheels of higher order being driven by the units wheel through the usual Geneva transfer movement. The driving ratio of the gears 180, 182, and 184 is such that for each rotational movement of the cam 130 through a distance of 45 degrees, the batch totalizer is actuated to register one unit of operation.

It will be recognized from the foregoing description that I have invented a novel register which may be preset to indicate a predetermined amount to be registered, and which operates at the termination of the predetermined registration to automatically condition itself preparatory to the initiation of a subsequent registering operation without the necessity of a resetting operation; that the register operates to indicate both the amount actually registered and the amount of the predetermined operation still to be registered at all times during the operation; and that the register is capable of controlling the operation of a device or system for a series of like predetermined operations; the register operating to cause the operation of the device or system, as the case

may be, to cease upon the termination of a predetermined operation, and to automatically repeat such control for any series of successive operations of like quantity or duration without 5 requiring to be reset or re-adjusted.

Although I have shown and described only one specific embodiment of my invention, I am fully aware that many modifications thereof are possible and that the novel register thereof is capable 10 of use for the the purpose of controlling operations of devices or systems quite different from the dispensing system disclosed. My invention, therefore, is not to be restricted except insofar as is necessitated by the prior art and the scope 15 of the appended claims.

I claim:

1. In a device having counting means operable in either a forward or reverse direction to a predetermined count, driving means therefor and a reversible connection for said driving means; the combination therewith of predetermining means adapted to be operated at the end of each counting operation, a cam driven by said driving means, an element movable to cam engageable position upon operation of said predetermining means, and means associated with said element to effect reversal of said connection when said element is actuated by said cam.

2. In a device having counting means operable in either a forward or reverse direction to a predetermined count, driving means therefor and a reversible connection for said driving means; the combination therewith of predetermining means adapted to be operated at the end of each counting operation, a cam driven by said driving means, an element movable to cam engageable position upon operation of said predetermining means, a latch, means releasable by said latch to effect reversal of said connection, and said latch being 35 actuated by said cam.

3. In a device having two counters operable simultaneously in opposite counting directions, each counter having a plurality of operably connected numeral wheels, and reversible driving means for said counters; the combination therewith of manual means operable to preset said counters, predetermining means adapted to be operated at the end of each counting operation 45 and control means operable upon operation of the predetermining means to reverse the reversible driving means, said control means having means to determine to which of said counters the manual means may be connected for presetting purposes.

CHARLES S. HAZARD.
